 In Hungary April 23, 1940

8 Claims. (Cl. 197—84)

The invention relates to improvements in typewriting machines and particularly to a device adaptable to such machines for varying the length of each advancing or spacing step initially imparted to the writing sheet by the step-by-step movement of the platen carriage.

With normal typewriting machines the length of the spacing step of the carriage and thereby of the writing sheet is constant. The main object of the present invention is to provide a typewriting machine provided with a device of simple design which works reliably and which can be mounted to the existing machine with small cost and which thereon permits its being adjusted to any desired variation of the length of the spacing step imparted to the writing sheet, which spacing step when so adjusted remains constant during the writing of the respective line, in order to equalize the lengths of the typewritten lines, which normally differ somewhat from each other and to cause all ends of the lines to be in alignment so that the typewritten text has in this respect the appearance of a printed page.

Another object of the invention is to provide a device which is constructed as a unitary structure attachable to existing typewriting machines, transforming thereby these machines of known design into improved typewriting machines having the aforementioned characteristics, such device being referred to as "adapter" in the claims relating thereto.

The device according to the invention comprises motion transmitting means obtaining their impulse from the movement of the carriage and being adjustable at will to vary the length of the spacing step imparted to the writing sheet to correspond to a predetermined value. These motion transmitting means comprise, according to the invention, positive driving means, for example a chain engaging a chain wheel, a rack engaging a pinion wheel, etc. the chain or rack being fastened to the frame of the typewriting machine, said positive driving means being adapted to rotate a member according to the stepwise displacement of the carriage, the axis of rotation of said rotatable member being fixed in relation to the carriage. This rotatable member, which can for example be a toothed wheel driven by the aforesaid chain wheel or pinion wheel or another pinion wheel keyed to the shaft of the aforementioned wheels, is provided with a piece, for example a pin, in sliding engagement with a member which can be displaced linearly by the aforesaid piece, if the point of

engagement of this piece is adjusted not to coincide with the axis of rotation of the rotatable member. The rotatable member is journalled to ensure its axis of rotation being in a fixed distance from the carriage, for example journalled in a casing rigidly fastened to said carriage. The said rotatable member is geared or driven in such a way that it should make at most one-half, preferably about one-quarter of a revolution during the travel of the carriage corresponding to the maximum number of spacing steps of a line. The point of engagement between the aforesaid piece and the linearly displaceable member can be adjusted at will in relation to the axis of rotation of the said rotatable member, for example toothed wheel. To this end, the toothed wheel may be provided with a threaded spindle rotatably but unslidably mounted thereon and being provided with a knob constituting the adjusting means. Said spindle can have a nut threaded unrotatably but slidably thereon and bearing a pin slidably engaging a slot provided in the linearly displaceable member. This member may be displaceable along guiding means mounted in the aforesaid casing, and provided with indicating means showing the adjustment of the device. The linearly displaceable member is connected to a shifting member adapted to correct the displacement of the writing sheet in relation to the frame of the typewriting machine in dependence of the adjusted distance of the point of engagement of the members in sliding engagement from the axis of rotation of the said rotatable member.

This shifting member may be the rack moving the carriage, if this rack is, according to the invention, slidably mounted on the carriage and rigidly connected to said linearly displaceable member. In this case, the aforesaid motion transmitting device is mechanically inserted between the rack and the carriage and therefore corrects the displacement of the whole carriage in relation to the rack, this rack being in engagement with the known mechanism adapted to impart the normal step-by-step movement to the rack.

Alternatively, the rack may be fixed to the carriage, as usual, but the means for holding the writing sheet may be laterally displaceable in relation to the carriage, and connected to said shifting member. In any case, the shifting member corrects the lateral displacement of the writing sheet in relation to the carriage of the typewriting machine, i. e. point of contact of the types acting on the writing sheet in accordance

to the adjustment of the device, for the purpose already set forth.

The variation of the length of the spacing step, i. e. the correction imparted to the displacement of the writing sheet may be effected by adding to or subtracting from the length of every step of normal advancing movement of the carriage or of the writing sheet, the amount of this addition or subtraction being adjustable.

Further objects of the invention will appear from the following description and from the accompanying drawings, describing and showing respectively several constructional examples of the subject matter of the present invention.

On the drawings—

Figs. 1-6 show a first embodiment, in particular,

Fig. 1 shows a typewriting machine, with the correcting device attached thereto, in perspective view and seen from the rear side;

Fig. 2 shows in elevation the device according to the invention built to form a unitary structure, a cover plate being omitted from the casing;

Fig. 3 is a vertical section along line III—III in Fig. 2;

Fig. 4 is a vertical section along line IV—IV in Fig. 2;

Fig. 5 shows a device according to the invention in different operative positions, a cover plate being omitted;

Fig. 6 is a diagrammatical front view of the device according to the invention;

Fig. 7 shows a vertical section of a cover;

Fig. 8 shows a diagrammatical rear view of a modification of the transmission means illustrated in Figs. 1-6;

Figs. 9 and 10 show diagrammatically further constructional examples in which the length of the spacing step is varied by the alteration of the position of the writing sheet.

In the first embodiment of the invention illustrated in Figs. 1-6 the variation in the length of the steps is obtained by the transmission means causing an additional displacement of the carriage relatively to the rack, the latter being endwise displaceably mounted in the carriage to permit such displacement.

The motion transmitting means are mounted in a casing 1 fixed as a unitary structure to the platen carriage 2 of a typewriting machine. 3 denotes the frame of the latter.

The rack 4 moving the carriage 2 is slideably mounted in the arms 5 of the carriage and can be laterally displaced in relation to the carriage 2 to an extent which corresponds to at least the sum of the maximal elongation and shortening of all the advancing steps of a line. For example the rack can be displaced laterally in relation to the carriage by the amount of say 10-20 advancing steps.

The pulley wheel 6 is rotatably journaled on a shaft fastened to the carriage 2, thereby constituting a free wheel. A chain wheel 7 is rotatably journaled in the casing 1 by means of its shaft 10. A chain 8 is fastened with both its ends to the plate 9 fastened to the frame 3. said chain running over the pulley wheel 6 and the chain wheel 7. The chain wheel 7 has a shaft 19 journaled in casing 1. This shaft 10 has keyed to its other end a small pinion wheel 11 positioned inside the casing 1 and meshing with another toothed wheel 12 of larger diameter (Figs. 2 and 3). This wheel 12 is rotatably journaled in casing 1 by means of its shaft 13, and

is preferably also laterally supported by bearing balls 14. The wheel or segment 12 is provided with the bearings 15, 15 and in these the spindle 16 is journaled rotatably but not slidably, i. e. not being displaceable in the direction of its axis. The upper end of this screw-threaded spindle extends through a corresponding elongated slot of the casing 1 and is provided with a knob 17 constituting the adjusting means of the device.

Threaded on the spindle 16 is a nut 18, contacting by means of its flat sliding surface 19 with the surface of the wheel 12, and therefore this nut cannot be rotated in relation to the spindle 16 but can be displaced in the direction of the axis of this spindle by rotating said spindle. On its side opposite to that bearing the sliding surface 19 the nut is provided with a pin 20 of preferably circular cross-section.

The casing 1 contains the sliding piece 22 guided on the guides 21 and linearly displaceable along these guides. This sliding piece 22 is provided with a slot 23 constituting sliding engagement means for the pin 20 of the nut 18, said pin being positioned in said slot. The sliding piece 22 is further provided with an arm 24 extending through a corresponding slot of the casing 1 out of said casing and being connected with the rack 4 slidably mounted in the arms 5 of the carriage 2.

On each advancing step of the carriage 2 the chain wheel 7 is rotated by means of the chain 8 by a certain angle corresponding to the advancement of the carriage in relation to the frame of the typewriter. On rotating, the chain wheel 7 rotated the pinion wheel 11, and the toothed wheel 12, and thereby also the spindle 16, which therefore swings, from its original, for example vertical position shown on Fig. 2, into another position, together with its nut and the pin 20 of the latter.

If the pin 20 is in the position shown in Figs. 2 and 4 in which position its axis coincides with the axis of rotation of the wheel 12, i. e. with the axis of the shaft 13, then the rotation of the wheel 12 only rotates the pin 20 round its own axis and therefore the sliding piece 22 is not displaced in relation to the casing 1 by such rotation of the pin 20 engaging the slit 23 of the sliding piece 22.

The step-by-step advance movement is imparted to the rack 4 in the manner usual in typewriting machines, by means of the known escape mechanism of the typewriter. The movement of the rack is transmitted by means of the arm 24 and the parts connected therewith to the casing 1 which in the relative positions of its parts shown on Figs. 2 and 4 is undisplaceable in relation to the arm 24, and from this casing the movement is transmitted to the carriage 2 of the typewriter to which the casing is rigidly fastened.

If therefore the extension 20 is in the position shown in Figs. 2 and 4, then the step-by-step movement of the rack 4 is transmitted by the casing 1 and all the parts contained therein, no relative movement of the arm 24 and the casing 1 taking place, and therefore the movement of the rack being transmitted unchangedly to the carriage 2. Therefore in this case the device according to the invention is out of function, and does not correct the advance movement of the writing sheet.

If, however, the pin 20 has been displaced by rotating the spindle 16 by means of its knob 17

and therefore its axis does not coincide any more with that of the shaft 13, then this pin moves on a curved path on each advance step of the carriage and therefore displaces the sliding piece 22 on each advance step of the carriage in relation to the casing 1. The extent of such displacement depends on the distance of the axis of the pin 20 from the axis of the shaft 13.

As the carriage 2 is laterally displaced by the rack 4 by means of the casing 1 and the parts contained therein, its displacement depends also on the relative displacement of the arm 24 and the casing 1. The displacement of the carriage 2 in relation to the frame 3 will therefore be the displacement resulting from the addition or subtraction of the relative displacement of the arm 24 and the casing 1 to the displacement of the rack 4. Obviously the direction of the relative displacement between casing 1 and arm 24 depends on the fact, whether the pin is in a position above or below the axis of rotation of the wheel 12, i. e., whether the pin 20 displaces the sliding piece 22 to the right or to the left. The value of this relative displacement depends on the distance of the pin 20 from the axis of the shaft 13, because the sliding piece 22 is displaced on each step by a value increasing with said distance.

Fig. 5 of the drawings shows a device according to the invention with omission of the covering front plate of the casing in two different working positions. In the position shown with full lines the pin 20 is in a position above the axis of rotation of the wheel 12 in the maximum possible distance from said axis of rotation. In the position shown in dotted lines the pin 20 is below this axis of rotation, also in its maximum possible distance therefrom. Assuming, for example, the spindle 16 being in its vertical position shown in the drawing, it will be clear that the rotation of the spindle 16 and thereby the displacement of the pin 20 displaces the sliding piece 22. The direction and extent of the displacement of the sliding piece 22 therefore depends on the direction and extent of displacement of the pin 20, displacement of the pin 20 upwards resulting in a displacement of the sliding piece 22 to the right and downward displacement of the pin 20 displacing the sliding piece to the left.

The sliding piece 22 is provided with a scale 25. The middle of said scale is marked with 0 and the scale bears numbers increasing to the right and left of said middle, one series of these members also being provided with the mark +, the other with the mark -. The covering front plate 26 of the casing 1 is provided with a window 27 through which readings of this scale may be taken (Fig. 6). The scale 25 and the window 27 are preferably mounted in such relative positions that in the position of the device shown in Fig. 2 exactly the middle of the scale can be seen through the window. On displacement of the pin 20 the sliding piece 22 and therefore also the scale 25 is displaced. Therefore the correction of the step-by-step movement of the carriage, i. e. the lengthening or shortening of each advance step obtained by means of the device can be read on this scale, such reading showing the sense and extent of the correction effected by the device.

The fastening of the casing 1 to the carriage 2 of the typewriter can be effected, as shown on Fig. 6, by means of the arm 29 of the carriage and by means of the connecting piece 29'.

It is sometimes desirable to displace the carriage 2 at will without thereby actioning the de-

vice according to the invention. To this end it is preferable to make the chain wheel 7 rotatable independently of its shaft 10, i. e., providing means for disconnecting at will wheel 7 from shaft 10. This may be done for example by providing chain wheel 7 with a further wheel 30 having notches on its circumference (Fig. 3). The rigidly interconnected wheels 7 and 30 are loose on shaft 10, said shaft being provided with an extension 31. This extension bears a two-arm lever 32, 33, arm 32 of this lever engaging on impulse of the spring 34 one of the notches of the wheel 30 and thereby locking wheels 30 and 7 to the shaft 10.

15 A head 35 extends through a slit provided in the back plate of the casing 1, said head being connected by means of the link piece 36 with a push button 37 extending upwards through the wall of the casing 1. The interconnected parts 35, 36 and 37 are held in their upper position shown in the drawing by the spring 38.

20 The head 35 is positioned near to the path of rotation of the arm 33, and therefore if this arm is under the head 35 and the button 37 is depressed against the action of the spring 38, the head 35 moves the arm 33 downwards against the action of the spring 34 thereby lifting arm 32 out of the notch of the wheel 30 and disconnecting wheels 30 and 7 from the shaft 10.

25 The chain wheel 7 may alternatively be provided with any suitable other locking means, such as a simple sleeve rotatable on shaft 10 and provided with suitable locking means, for example a screw, which can be actuated by hand to lock said sleeve and therewith wheel 7 to the shaft. This locking device can be actuated in any position of the wheel 7.

30 For protecting the chain wheel 7 and the parts connected therewith positioned outside of the casing 1 a cover 39 may be provided on the casing. This cover is shown on Fig. 7 and may be fastened to the casing 1 in any suitable manner and provided with openings 39' for the chain 8. Such covering may also be useful when mounting the device to prevent faulty running or jumping of the chain 8.

35 Instead of driving shaft 10 of the pinion wheel 11 by means of a chain wheel 7 and chain 8 as shown on Figs. 1-6, this shaft can also be driven by other positive driving means, for example by a pinion wheel 43 shown on Fig. 8. Said pinion wheel takes the place of chain wheel 7 on shaft 10 and engages a rack 41 fastened to the frame 3 of the typewriting machine.

40 In the constructional examples of the device according to the invention shown and described in connection with Figs. 1-7 of the drawings, the carriage of the typewriter obtains an additional or correcting displacement in order to lengthen or shorten each advance step of the carriage itself. As it is however only essential to correct the displacement of the writing sheet in relation to the frame of the typewriting machine in order to lengthen or to shorten each advance step of the writing sheet, the device according to the invention can also be constructed to leave the normal advance movement of the carriage unaltered, i. e., uncorrected, and to correct only the advance of the writing sheet. To this end the carriage advancing mechanism is left unchanged, and the correction is imparted to a member of the carriage bearing the writing sheet. An example of such a device is shown on Fig. 9.

45 In the construction shown on Fig. 9 the platen

42 of the carriage 2 comprises telescopically engaging parts 42 and 43. The part 43 is in the form of a sleeve which is unrotatable but axially slidable in relation to the platen part 42. To this end, projections 44 of the platen part 42 may engage longitudinal grooves 45 of the sleeve 43. Sleeve 43 is provided with an annular extension 46, engaging the forked end of the rod 47. The other end of this rod is connected with the arm 24 extending out of the casing of the device according to the invention. The rack 4 displacing the carriage 2 step-by-step is connected rigidly with the carriage in this case and therefore the length of each advance step of the carriage is constant. The arm 24 of the sliding piece 22 however is displaced on each advance step, according to the adjustment of the pin 20, with a predetermined value to the right or to the left, and therefore displaces by means of the rod 47, the sleeve 43 in relation to the platen part 42 by the same value. The advance steps of the writing sheet held by the sleeve 43 are therefore shortened or lengthened in relation to the advance step of the carriage according to the adjustment of the device according to the invention. To enable this, the rollers 48 pressing the writing sheet to the sleeve 43 must be disposed in a manner allowing their lateral displacement together with the sleeve 43, and therefore must be slidably mounted on their shafts.

Alternatively it is also possible to make the platen part 42 laterally displaceable in relation to the carriage 2, as shown for example on Fig. 9 of the drawings. In this case the platen part 42 is laterally displaced in relation to the carriage 2 in a manner similar to that described in connection with Fig. 8, i.e., by means of the rod 47 engaging with its forked end the annular extension 49 of the platen part 42. The rollers 48 pressing the writing sheet to the platen part 42 are laterally displaceable in relation to the carriage in order to be displaced together with the platen on lateral displacement of the same.

In order to use the typewriting machine provided with any of the above described devices for varying the spacing steps imparted to the writing sheet, the writing is first done with the device in its inoperative position shown in Fig. 2 in which the axis of the pin 20 coincides with the axis of rotation of the toothed wheel 12. The written lines will be unequal in length and they have now to be rewritten to obtain equal lengths. If it is intended to write lines of the equal lengths of say 60 normal spacing steps, and the line written while the device is in its inoperative position has a length of say 56 normal advancing steps, each of the 56 spacing steps of the line referred to must be increased by an increment of $\frac{1}{6}$ of its normal value, so that the larger 56 spacing steps will equal the 60 normal steps. In similar manner a line which has the length of say 62 normal spacing steps has to be shortened by adjusting the device to decrease each spacing step by $\frac{1}{62}$ of its normal value, so that the decreased 62 spacing steps will equal to the 60 normal spacing steps.

We wish it to be understood that we do not desire to be limited to the exact details of construction shown and described, for obvious modifications will occur to a person skilled in the art.

In the claims affixed to this specification no selection of any particular modification of the invention is intended to the exclusion of other

modifications thereof and the right to subsequently make claim to any modification not covered by these claims is expressly reserved.

We claim:

5 1. In a typewriter or the like having a member movable step by step, an escapement mechanism for controlling the step by step movement of said member, motion transmitting means between the escapement mechanism and said member to vary the length of the step by step movements thereof, comprising a second member controlled by the escapement mechanism and connected to the first member for movement relative thereto, a revolute element movable with the first member, means for imparting a rotative movement to said revolute element in response to movement of the first member in the direction aforesaid, a device supported for sliding movement in the direction aforesaid and connected to the second member, guide means on said device inclined with respect to the direction of movement thereof, a part rotatable with the revolute element and slidably engaging said guide means, and means for adjusting said part along the guide means from a position coincident with the axis of the revolute element to a position spaced from the axis of the latter element.

10 2. In a typewriter or the like having a member movable step by step, an escapement mechanism 15 comprising a second member controlled by the escapement mechanism and connected to the first member for movement relative thereto, a revolute element movable with the first member, means for imparting a rotative movement to said revolute element in response to movement of the first member in the direction aforesaid, a slide supported for sliding movement along a path parallel to the movement of the first member and connected to the second member, said slide having a slot inclined with respect to the direction of sliding movement thereof, a part rotatable with the revolute element and extending through said slot for sliding engagement with opposite side walls of the latter, and means for adjusting said part along the slot 20 from a position coincident with the axis of the revolute element to positions at either side of the axis of the revolute element.

25 3. In a typewriter or the like having a carriage movable step by step, escapement mechanism 30 controlling the step by step movement of said carriage, motion transmitting means between the escapement mechanism and said member to vary the length of the step by step movements thereof, comprising a rack controlled by the escapement mechanism and connected to the carriage for movement relative thereto, a revolute element movable with the carriage, means responsive to movement of the carriage for imparting a rotative movement to said element, a slide supported for sliding movement in a path parallel to the path of travel of the carriage and connected to said rack, guide means on said slide inclined with respect to the direction of movement of the slide, a part rotatable with the revolute element and slidably engaging said guide means, and means for adjusting said part along the guide means from a position coincident with the axis of the revolute element to a position spaced from the axis of said element.

35 4. In a typewriter or the like having a mem-

ber movable step by step, an escapement mechanism for controlling the step by step movement of said member, motion transmitting means between the escapement mechanism and said member to vary the length of the step by step movements thereof, comprising a second member controlled by said escapement mechanism and connected to said first member for movement relative thereto, a revolute toothed element movable with the first member, a driving gear rotatable in response to movement of the first member in the direction aforesaid and meshing with the teeth on the revolute element for imparting a rotative movement to the latter, a slide supported for sliding movement in a path parallel to the path of travel of the first member and connected to the second member, guide means on said slide extending transversely to the path of movement of the slide, a part rotatable with the revolute element and slidably engaging said guide means, and means for adjusting said part along the guide means from a position coincident with the axis of the revolute element to a position spaced from the axis of the latter element.

5. In a typewriter or the like having a carriage, movable step by step an escapement mechanism for controlling the step by step movement of said carriage, motion transmitting means between the escapement mechanism and said carriage to vary the length of the step by step movements thereof, comprising a rack controlled by said escapement mechanism and connected to the carriage for movement relative thereto, a revolute toothed element movable as a unit with the carriage, a drive gear rotatable in response to movement of the carriage in the direction aforesaid and meshing with the teeth on the revolute element for rotating the latter, a slide supported for sliding movement in a path of travel substantially parallel to the path of travel of the carriage and connected to the rack, said slide having an elongated slot extending transversely to the path of travel of the slide, a part rotatable with the revolute element and extending through the slot for sliding engagement with opposite side walls of said slot, and means for adjusting said part along the slot from a position coincident with the axis of the revolute element to positions spaced from the axis of the latter element.

6. In a typewriter or the like having a member movable step by step, an escapement mechanism for controlling the step by step movement of said member, motion transmitting means between the escapement mechanism and said member to vary the length of the step by step movements thereof, comprising a second member controlled by the escapement mechanism and connected to the first member for movement relative thereto, a revolute element movable with the first member, means responsive to movement of the first member in the direction aforesaid and imparting a rotative movement to said revolute element, a slide supported for sliding movement in a path of travel substantially parallel to the path of travel of the first member and connected to the second member, guide means on said slide extending transversely of the path of travel of the slide, a third member carried

5 by the revolute element and slidable relative to the revolute element transversely of the axis of said element, said third member having a portion engaging the guide means, and means for adjusting said third member relative to the revolute element to vary the location of the portion aforesaid of the third member relative to the axis of the revolute element.

7. In a typewriter or the like having a member movable step by step, an escapement mechanism for controlling the step by step movement of said member, motion transmitting means between the escapement mechanism and said member to vary the length of the step by step movements thereof, comprising a second member controlled by the escapement mechanism and connected to the first member for movement relative thereto, a revolute element movable with the first member, means responsive to movement of the first member in the direction aforesaid for imparting a rotative movement to said revolute element, a slide supported for sliding movement in a path of travel substantially parallel to the path of travel of the first member and connected to the second member, guide means on said slide extending transversely of the path of travel of the slide, a nut mounted on the revolute element for sliding movement transversely of the axis of said element and having a portion slidably engaging the guide means on said slide, and a screw carried by the revolute element perpendicular to the axis of the latter and threadedly engaging the nut for adjusting the location of the portion aforesaid of said nut relative to the axis of the revolute element.

8. In a typewriter or the like having a carriage, movable step by step, an escapement mechanism for controlling the step by step movement of said carriage, motion transmitting means between the escapement mechanism and said carriage to vary the length of the step by step movements thereof, comprising a rack controlled by the escapement mechanism and connected to said carriage for movement relative thereto, a revolute toothed element movable as a unit with the carriage, a drive gear rotatable in response to movement of the carriage in the direction aforesaid and meshing with the teeth on the revolute element, a slide supported for sliding movement in a path of travel substantially parallel to the path of travel of the carriage and connected to said rack, said slide having an elongated slot extending transversely to the path of travel of the slide, a nut carried by the revolute element at one side of the latter for sliding movement transversely of the axis of the revolute element and having a pin extending parallel to the axis of the revolute element and projecting through the slot in said slide, a screw carried by the revolute element with its axis extending perpendicular to the axis of said element and threadedly engaging the nut, and means for rotating the screw to adjust the nut relative to the revolute element and thereby vary the position of the pin with respect to the axis of the revolute element.
